United States Patent Office

Des. 177,650
Patented May 8, 1956

177,650

AUTOMOBILE

Clifford Brooks Stevens, Milwaukee, Wis.

Application October 10, 1955, Serial No. 38,317

Term of patent 3½ years

(Cl. D14—3)

Des. 177,650

I claim:

The ornamental design for an automobile, as shown.
